(57) **CLAIM**

The ornamental design for a lens for television camera as shown and described.

DESCRIPTION

FIG. 1 is a perspective view from upper and right side of a lens for television camera, showing our new design;

FIG. 2 is a perspective view from upper and left side thereof;

FIG. 3 is a perspective view from lower and right side thereof;

FIG. 4 is a perspective view from lower and left side thereof;

FIG. 5 is a front view thereof;

FIG. 6 is a rear view thereof;

FIG. 7 is a top plan view thereof;

FIG. 8 is a bottom plan view thereof;

FIG. 9 is a right side view thereof; and,

FIG. 10 is a left side view thereof.

The broken lines illustrate portions of the lens for television camera and form no part of the claimed design.

1 Claim, 8 Drawing Sheets
